FIG. 1.

FIG. 3.

FIG. 2.

Inventor

HEYMAN ROSENBERG

By Edgar M. Kitchin

his attorney.

UNITED STATES PATENT OFFICE

HEYMAN ROSENBERG, OF NEW YORK, N. Y.

DAMPER

Application filed August 20, 1931. Serial No. 558,411.

This invention relates to improvements in those features of damper construction relating to the mode of mounting and method of operation, and the primary object in view is the simplification and reduction in cost of dampers while improving efficacy of operation.

With this and further objects in view, the invention includes in combination with a damper plate means for adjusting the damper angularly, means for guiding the movement of the parts in their adjustment, and means for clamping the several parts in any of various adjusted positions.

In greater detail, the invention includes an operating lever or handle having a sleeve adapted to surround a damper rod, an annulus surrounding the rod and providing a bearing for the sleeve, and means for clamping the sleeve and annulus in any position of adjustment of the sleeve.

The invention comprises certain other novel constructions, combinations, and arrangements of parts as will hereinafter become apparent and subsequently be pointed out in the appended claims.

In the accompanying drawing,—

Figure 1 is a transverse section through a flue to which an embodiment of the present invention has been applied, the damper being seen in plan, and parts being broken away and seen in section.

Figure 2 is a vertical section through the parts seen in Figure 1, the damper plate and bearing rods being seen in elevation.

Figure 3 is an enlarged, detailed elevation of the serrated face of the annulus.

Referring to the drawing by numerals, 1 indicates a flue, chimney, or other duct or passage whose draft is to be controlled, and 2 indicates the damper plate which, of course, preferably conforms to the cross section of the flue 1, and is of sufficiently reduced circumference to swing freely within the flue, a relatively small space 3 being left between the damper plate 2 and the inner surface of the flue 1. The plate 2 is sustained by a damper rod which may be of the conventional form, but is preferably formed of separate pieces fixed to the plate 2, one of said

pieces consisting of a rod section 4 outstanding through the flue 1 and finding bearing therein and having an enlarged, connecting tab 5 appropriately fixed, as by riveting, bolting, or the like, to the damper plate 2. The other section of the damper rod consists of a tab 6 similar to tab 5 and preferably detachably connected to the plate 2 for convenience of mounting the plate, a rod section 7 outstanding from the tab 6 through and finding bearing in the wall of the flue 1. Preferably the rod 7 is provided with an enlarged boss 8 between the tab 6 and the inner wall of the flue 1, the boss being formed with a curved outer face 9, that is a partiglobular face struck on an arc corresponding to the curvature of the wall of the flue 1, so that a horizontal line of contact between said outer face of boss 8 and the flue 1 will at all times be maintained notwithstanding angular adjustments of the plate 2, and, therefore, when the damper plate 2 is subject to a stress tending to draw it in the direction of the axis of the damper rod, the outer face of the boss 8 will serve as a resistance wall in contact with the inner face of flue 1, and the damper plate 2 will therefore not be drawn toward the inner surface of the flue 1 at one point appreciably closer than at any other point.

The damper rod 7 is preferably formed with a cylindrical portion 10 providing the bearing engagement with the wall of flue 1 and outstanding a short distance therefrom, and beyond the cylindrical portion 10 the rod is formed with a squared or other poly-sided portion 11, and still outward from the portion 11 the rod is formed into a threaded bolt 12 engaged by a nut 13 preferably of the wing-nut type to facilitate manual operation. Surrounding the cylindrical portion 10 is an annulus 14 conforming at its inner face in contour with the adjacent contour of the wall of flue 1 so that the inner face of the annulus 14 is curved in one direction, as seen in Figure 1, and relatively straight in the other direction, as seen in Figure 2, and the said face of annulus 14 is preferably provided with serrations or teeth 15, as seen in Figure 3, which are

adapted to slightly embed themselves in the engaged surface of the flue 1 to prevent the annulus from slipping or having any tendency toward rotary movement. Naturally, 5 the curvature of the annulus in one direction only will also contribute to preserving the annulus against rotation, and as a means of more effective engagement the teeth 15 are preferably case-hardened. The annulus 10 14 is provided with an outstanding, annular boss or hub portion 16. A sleeve 17 surrounds the extended portion of rod 7 and is provided with a passageway snugly receiving the polysided portion 11, so that the 15 sleeve 17 may move in an axial direction on the rod while requiring the rod to move angularly with angular movement of the sleeve. The outer end portion of the sleeve 17 is sufficiently reduced to permit free but 20 comparatively snug passage of the reduced bolt portion 12 of rod 7, and the nut 13 is located to engage the outer end of the sleeve for stressing the same toward the flue 1 as the nut is rotated inward. The inner end 25 portion of sleeve 17 is enlarged and surrounds and finds bearing on the boss or hub portion 16 with the inner end of the sleeve resting against the outer face of the annulus 14. The annulus and its boss 16 serve 30 also as a bearing for the cylindrical portion 10 of the damper rod. An operating handle or lever 18 extends from the sleeve 17 to facilitate oscillating or angular adjustment of the parts, and an appropriate eye 19 is 35 provided in sleeve 17 to facilitate adjustment of an appropriate operating cable when desired.

The operation is very simple and will be 40 readily understood from the foregoing.

40 Tightening nut 13 causes sleeve 17 to clamp annulus 14 against the outer face of flue 1, while the boss 8 has its outer face clamped against the inner face of flue 1, and thus the parts may be frictionally locked against 45 movement for retaining damper plate 2 in any given adjusted position. When it is desired to shift the plate, if the clamping action has not been too severe, the movement of the parts may be accomplished by merely 50 overcoming the friction between sleeve 17 and annulus 14 and between boss 8 and wall of flue 1, but ordinarily the operator will loosen back on the nut 13 to allow freer movement of the parts. The lever 18 is 55 swung as required, rod 7 accordingly manually adjusted, and the damper plate 2 moved therewith to the required new position, and then the nut 13 is again tightened, clamping the parts in the new location.

60 During such annular movement, the enlarged portion of sleeve 17 will have moved about the boss or hub 16 as a bearing, and thus prevented any possible lateral or bending strain on the damper rod.

What is claimed is:—

1. In damper construction, the combination, with a damper plate and damper rod adapted to outstand through the wall of a flue, of a sleeve slidably and non-rotatingly engaging the rod, a nut threaded onto the rod beyond the sleeve for effecting a relatively clamping action between the sleeve and damper plate, and an annulus surrounding the rod and providing a bearing therefor, directly engaging the rod, the annulus also providing a seat for the end of the sleeve. 70

2. In damper construction, the combination, with a damper plate and damper rod adapted to outstand through the wall of a flue, of a sleeve slidably and non-rotatingly engaging the rod, a nut threaded onto the rod beyond the sleeve for effecting a relatively clamping action between the sleeve and damper plate, and an annulus surrounding the rod and providing a bearing therefor, directly engaging the rod, the annulus having an outstanding hub-like boss extending into and providing bearing for the sleeve, the sleeve extending to and engaging the face of the annulus. 80

3. In damper construction, the combination, with a damper plate and damper rod adapted to outstand through the wall of a flue, of a sleeve slidably and non-rotatingly engaging the rod, a nut threaded onto the rod beyond the sleeve for effecting a relatively clamping action between the sleeve and damper plate, and an annulus surrounding the rod and providing a bearing therefor, directly engaging the rod, the annulus having an outstanding hub-like boss extending into and providing bearing for the sleeve, the sleeve extending to and engaging the face of the annulus, said rod having a boss located to lie inward of the flue. 90

4. In damper construction, the combination, with a damper plate and damper rod adapted to outstand through the wall of a flue, of a sleeve slidably and non-rotatingly engaging the rod, a nut threaded onto the rod beyond the sleeve for effecting a relatively clamping action between the sleeve and damper plate, and an annulus surrounding the rod and providing a bearing therefor, directly engaging the rod, the annulus having an outstanding hub-like boss extending into and providing bearing for the sleeve, the sleeve extending to and engaging the face of the annulus, the annulus having its face presented toward the flue shaped to conform to the engaged surface of the flue and being provided with serrations for engaging the flue and resisting rotation of the annulus. 100

HEYMAN ROSENBERG.
